HANDBAG

William H. Hardy, River Edge, N. J.

Application May 29, 1950, Serial No. 10,260

Term of patent 7 years

(Cl. D87—3)

To all whom it may concern:

Be it known, that I, William H. Hardy, a citizen of the United States, residing in River Edge, in the county of Bergen and State of New Jersey, have invented a new, original, and ornamental Design for a Handbag, of which the following is a specification, reference being had to the accompanying drawing, forming part thereof.

Fig. 1 is a front perspective view of a handbag showing my new design, and

Fig. 2 is another perspective view thereof as it appears in opened position.

The back of the handbag is substantially plain and the side view not shown is identical to the side disclosed.

I claim:

The ornamental design for a handbag, substantially as shown and described.

WILLIAM H. HARDY.
